UNITED STATES PATENT OFFICE.

WILLIAM A. BEAVAN, OF PHILADELPHIA, PENNSYLVANIA.

HOLDER FOR THE RECEIVER OF A TELEPHONE.

No. 853,672.

Specification of Letters Patent.

Patented May 14, 1907.

Application filed December 28, 1906. Serial No. 349,774.

To all whom it may concern:

Be it known that I, WILLIAM A. BEAVAN, a citizen of the United States, residing in the city and county of Philadelphia, State of Pennsylvania, have invented a new and useful Holder for the Receiver of a Telephone, of which the following is a specification.

My invention has for its object the support of the receiver of a telephone, when required for use, without the employment of the hand and the location of the same so that the ear may be placed close to the said receiver, while the mouth is at the transmitter of the telephone.

15 To this end, the invention consists of a device which is adapted to be connected with a member of the transmitter and hold the receiver in position to accomplish the above, said device being of a simple, light and inexpensive construction, as will be hereinafter described, its novel features being pointed out in the claims.

Figure 1 represents a perspective view of a holder for a telephone receiver embodying my invention, including the receiver and portion of the transmitter shown in dotted lines. Fig. 2 represents a perspective view of said holder taken in an opposite direction from that shown in Fig. 1.

30 Similar letters of reference indicate corresponding parts in the figures.

Referring to the drawings: A designates an arm, having at one end the bifurcation B, and at the other end, the seats C and C', said arm being formed of parallel members D, D, connected by the clips E, E, which tightly embrace said members as one, and prevent their separation.

The members forming the bifurcation B are bent down respectively from the members of the arm A and spread laterally whereby the resultant bifurcation may straddle say the screw B' which forms the joint of the mouth piece of a telephone transmitter and the stand thereof, said screw, mouth piece and a portion of the stand being shown in dotted lines.

50 The end of one of the members D opposite to the bifurcation is bent downwardly forming the seat C. The end of the other member is bent laterally forming the limb F, at whose terminal is the downwardly bent seat C'.

It will be seen that the seats C and C' are spaced apart, forming a broad support, whereby when there is a call, the telephone

receiver is removed from the arm of the stand, and then properly rested on the seats C, C', after which, the ear may be placed conveniently close thereto, while the mouth is 60 at the transmitter, the receiver thus being held without the use of the hand, it being also noticed that the receiver is controlled against slipping from the support, as the shoulders on its opposite end portions engage 65 with and are held between the seats C and C'.

In practice, the holder is formed of pieces of heavy wire or light round metal, thus avoiding weight and producing an inexpensive and simply-constructed article for the 70 purpose intended.

When the screw B' is loosened, the holder may be readily removed from the transmitter, and again as readily reapplied, adjusted and secured in position.

75 The limb F serves to space the seats C, C', to the distance required by the length of the telephonic receiver, and locate the latter to such extent to the front that the ear may be placed close to the same and without inconvenience or discomfort to the body.

In order to prevent rattling or other objectionable sounds by reason of the connection of the holder with the instrument or when the receiver is supported by the seats 80 C, C', I may provide the same and also the bifurcation B with some suitable material which will overcome the objection and in the drawings I have shown rubber casings G applied to the parts which will accomplish the 90 purpose.

It will be evident that various changes may be made by those skilled in the art which will come within the scope of my invention, and I do not therefore desire to be limited to 95 the exact construction herein shown and described.

Having thus described my invention, what I claim as new and desire to secure by Letters Patent, is:—

100 1. In a device of the character described, longitudinally extending arms, means for securing said arms together, a member deflected for an end of each arm forming a bifurcation, and a seat on each of said arms forming means for supporting a telephone receiver.

110 2. In a device of the character described, longitudinally extending arms, means for securing said arms together, a member deflect- ed for an end of each arm forming a bifurcation between which is adapted to be seated

the screw of a telephone, a seat on the other end of one arm, a limb extending at an angle from the other end of the other arm and a seat on said limb.

5. 3. A support for a telephonic receiver composed of an arm formed of a plurality of longitudinally extending pieces, a plurality of members, each deflected from an end of one of said pieces, forming a bifurcation, a seat on the other end of one of said pieces, a limb extending laterally from the end of the other piece, and a seat on the terminal of the latter, said seats being spaced apart.

4. In a device of the character described, longitudinally extending arms, means for securing said arms together, a member deflected for an end of each arm forming a bifurcation, a seat on each of said arms forming means for supporting a telephone receiver and a protector carried by the bifurcation and by the seats. 15 20

WILLIAM A. BEAVAN.
